UNITED STATES PATENT OFFICE

2,419,785

FOOTWEAR

Roy Maling, West Roxbury, Mass.

Application December 9, 1944, Serial No. 567 361

3 Claims. (Cl. 36—17)

1

This invention relates to improvements in foot-wear and more especially to shoes and slippers having a platform base element and a flexible sheet element extending over the bottom and sides of the platform base element and secured to the lower edge portion of the upper all around the extent of the upper.

It is an object of the invention to simplify shoe-making procedures and to obtain an improved shoe structure wherein a platform base element provides arch support for a foot in the shoe and a flexible sheet element encloses the platform base element and provides the tread surface of the shoe.

Another object is to provide an improved base structure for shoes and slippers including a platform and heel unit enclosed within a tread element which is adapted to be stitched or laced to an upper all around the article and well up out of the tread plane of the article.

It is, moreover, my purpose and object generally to improve upon prior shoe-making methods and prior footwear constructions.

In the accompanying drawings:

Figure 1 is a side elevation of a shoe embodying features of my invention.

Figure 2 is a side elevation of a modified construction which also embodies structural features of my present invention:

Figure 3 is a cross-sectional view on line 3—3 of Fig. 1.

Figure 4 is a cross-sectional view on line 4—4 of Fig. 2.

Fig. 5 is a medial longitudinal cross-sectional view through the above area.

View through the shoe of Figure 1;
Figure 6 is a side elevation of the upper of the
shoes of Figs. 1 through 5.

shoes of Figs. 1 through 5 prior to attachment of the base structure;

Figure 7 is a bottom plan view of the upper of Figure 6;

Figure 8 is a cross-sectional view on line 8-8 of Figure 6; and Figure 9 is a

Figure 9 is a fragmentary sectional view on line 9—9 of Figure 7.

Referring to the drawings, the upper 10 as shown has no lining and is stitched at 12 to the sock lining 14 throughout its extent around the shoe. At the back of the upper a separate piece of sheet material 16 is stitched exteriorly to the upper across its top at 18 and along both side edges as at 20, thereby to provide an exterior counter-receiving pocket 22 open at its bottom for insertion of a counter 24 between the upper and the piece 16. Any desired size of sheet 16 may be employed to provide an exterior counter.

pocket of size to receive any predetermined size of counter.

Obviously, the upper 10 might have a lining if desired, in which case the lining would be stitched to the sock lining 14 along with the upper.

As represented, a full length matted fibre platform element 26 has a heel lift 28 secured at its under side, and the platform 26 engages the usual counter flange 25 to hold the counter in place.

10 In Figs. 1, 3 and 5, the platform and heel unit
25, 28 may be loosely enclosed within a flexible
covering element which comprises a leather split
soft-sole tread element 30 to whose edges are se-
cured the turned up extensions 32 which may be
15 of leather or fabric or any other suitable flexible
material. The soft-sole element 30 surfaces the
full under area of the unit, and the extensions 32
are secured by stitching or preferably by lacing,
as shown at 34, to the lower edge of the upper 10
20 all around the extent of the upper. As a result,
the platform and heel unit needs to have no di-
rect attachment to either its enclosing flexible
covering element or to the upper or sock lining,
yet it is securely retained in operative position by
25 being bound in by the laced or stitched secure-
ment of the covering element to the upper.
This provides an extremely flexible shoe in which
parts can adjust themselves relatively during
flexing ensuring a superior degree of comfort for
30 the wearer.

If desired, a mere daub of cement between the sock lining and platform at the toe region and similar daubs of cement between the sock lining and platform in the heel region and between the platform and tread sheet at the forepart and rear part, may be employed to promote stability and to aid in assembly of parts.

In Figs. 2 and 4, I have illustrated the upper 40 secured on a base structure having a flat tread surface from front to rear of the shoe. The base structure comprises a platform and heel unit enclosed within a flexible covering sheet which may be oiled leather comparable to what is employed for moccasin soles. The covering sheet faces the 45 full under area of the platform and heel unit as at 30' and is turned up over the edges of the unit as at 32'. Suitable cutouts are made in the turned up portions 32', and the edges at the cutouts are brought together and stitched as at 36 50 to attain a smooth and tight fit of the cover around the platform and heel unit.

In both of the illustrated embodiments, I prefer to provide exteriorly on the upper 10, all around its lower edge, a strip 38 of leather for constituting an attaching strip or welt to which

the base structure may be stitched or preferably laced as shown. In the case of a laced securement, the strip 38 may have holes preliminarily punched therein as indicated at 40 to facilitate the lacing of the cover strip extensions 32, or the corresponding portions 32' of the integral sheet form, having similar punched holes 42 all along their edges.

I claim as my invention:

1. An article of footwear comprising an upper, a sock-lining having its marginal regions stitched to the lower edge regions of the upper, a welt strip stitched exteriorly to the lower edge of the upper around at least a substantial portion of the extent of the upper and turned outward into a generally horizontal position, a platform unit, flexible means covering the entire bottom area of said unit and having marginal portions turned upward into covering relation to the sides of said unit, and means passing through said welt strip securing said upturned marginal portions of said flexible means to the welt strip, said securing means being free from extent through any portion of the flexible covering means which is below the plane of the bottom of the platform unit.

2. An article of footwear comprising an upper, a welt strip stitched exteriorly to the lower margin of the upper around at least a substantial portion of the extent of the upper, said strip being turned outward into a laterally projecting position, a platform element disposed below the general plane of said laterally projecting strip, flexible means surfacing the under side of said platform element and extending generally upward over the sides of said platform element to said general plane of the laterally projecting welt strip, and means lacing the upper margin of said flexible means to said welt strip throughout the extent of said welt strip.

3. An article of footwear comprising an upper 40

and a sock lining stitched together around at least a substantial extent of the upper, a welt strip stitched exteriorly to the lower margin of the upper around said substantial extent of the upper and turned over the stitch line into a position in which it covers the stitches and projects outwardly at the lower margin of the upper, a platform unit underlying the sock lining, and flexible means covering the bottom of said unit and extending upward in covering relation to the sides of said unit, and securing means extending through the said welt strip and through the said flexible means and over the edges of said strip and flexible means, said securing means drawing together and maintaining them together with said securing means exposed at intervals crossing said edges.

4
ROY MALING.
